UNITED STATES PATENT OFFICE

LINUS C. HIRT, OF DES MOINES, IOWA.

COMBINATION PHONOGRAPH CABINET AND CHAIR.

Application filed January 11, 1922. Serial No. 528,547.

To all whom it may concern:

Be it known that I, LINUS C. HIRT, a citizen of the United States, and a resident of Des Moines, in the county of Polk and State of Iowa, have invented a certain new and useful Combination Phonograph Cabinet and Chair, of which the following is a specification.

The object of my invention is to provide a combination phonograph cabinet and chair of simple, durable and inexpensive construction in which an upholstered arm chair of substantially standard proportions may be utilized as a cabinet for a phonograph and set of records in such a manner that when the device is being used as a chair the compartments for containing the phonograph and records are closed and protected against the entrance of dust and dirt, and the entire exterior of the chair is covered with upholstery and is strong and durable enough to withstand all of the ordinary strains that are usually applied to upholstered arm chairs.

A further object is to provide a device of this kind whereby the occupant of the chair may readily, quickly and easily open the cover for either the phonograph compartment or the record compartment or both in such a manner that access may be had to either or both of the said compartments in such a manner that the operator may while maintaining his seat in the chair conveniently and easily operate the phonograph and remove or replace records from the record compartment.

A further object is to provide a device of this class in which the sounds from the phonograph may normally be projected through the open front of the upholstery with a somewhat muffled effect, or if a loud tone is desired, the upholstery covering the front of said arm portion may be removed.

My invention consists in the construction, arrangement and combination of the various parts of the device, whereby the objects contemplated are attained, as herein-after more fully set forth, pointed out in my claim and illustrated in the accompanying drawings, in which:

Figure 1 shows a top or plan view of the complete chair and cabinet device with the covers for both the phonograph compartment and the record compartment open in the position which they assume when in use.

Figure 2 shows a front elevation of the complete chair and cabinet.

Figure 3 shows a detail sectional view on the line 3-3 of Figure 2 with the upholstery removed, and illustrating the interior construction of the phonograph compartment.

Figure 4 shows a sectional view on the line 4-4 of Figure 3, illustrating the construction of the record compartment, and

Figure 5 shows a sectional view on the line 5-5 of Figure 1.

Referring to the accompanying drawings, I have used the reference numeral 10 to indicate generally the supporting base of the chair and cabinet. Secured to the back end thereof is a back frame member 11 and secured to the front is a front frame member 12, shown in Figure 2, covered with upholstery.

Mounted upon the central portion of the supporting base is a spring cushion seat 13 and supported by the back frame member 11 is an upholstered back member 14.

As will be seen by the drawings, there are two arm rests, each of which is substantially cylindrical in general outline. The arm rest on one side is designed to serve as a cabinet for phonographic records and that on the other side a cabinet for a phonograph. The arm rest that is designed to be used as a cabinet for phonograph records comprises a stationary circular hub member 15 secured to the frame member 11, and secured to the front surface thereof is a stationary disk shaped end member 16. At the front there is a similar stationary disk shaped supporting member 17 secured to the main frame and attached to its rear face is a stationary, circular hub member 18, and attached to the rear face thereof is a stationary disk shaped end member 19.

Surrounding each of the hub members 15 and 18 is a circular rotatable cover support 20. Secured to the peripheries of each of the supports 20 is a cylindrical rigid cover 21. This cover extends approximately three-fourths of the way around the cover supports leaving an open space at one side, as indicated at 22 in Figure 2. By this arrangement it is obvious that an operator

seated upon the cushion 13 may grasp the cover 21 and rotate it, for instance, from the position shown in Figure 5 where access to the interior of the record cabinet 5 may be readily had, to a position in which the open portion 22 is at the bottom and the entire arm rest is enclosed from a point slightly beneath the seat all around the top and outer side to a point adjacent to 10 the bottom of the arm rest position so that the record cabinet is thereby wholly enclosed either by the cover 21 or by the cushion 13 or the stationary frame of the chair. I also preferably provide a means 15 whereby the movement of the cover 21 may be regulated.

Referring to Figure 6 of the drawings, I have shown a detachable pin 23 in the front cover support 20, and the stationary 20 end 19 adjacent thereto is provided with two shoulders 24 and 25 to engage the pin and thus limit the movement. If for any reason it is desired to move the cover farther than the limitations of the pin, the pin may 25 be detached.

To adapt the device for convenient use as a phonograph record holder I preferably provide at the bottom of the rotatable cover supports a base 26 attached to the stationary 30 end members 16 and 19 and extending longitudinally of the seat, and at intervals on this base are uprights 27 to thereby support records 28 in substantially upright position resting against said supports or against the 35 end pieces 16 and 19.

The arm member that is designed to be used as a phonograph cabinet is of the same outward appearance as the other arm member before described, and has at the rear a 40 stationary hub 15 and a stationary end member 16 and a rotatable cover support 20, but at the forward end the structure is somewhat different, as clearly illustrated in Figure 3.

45 Instead of the structure at the front of the phonograph record cabinet I provide a stationary circular rim 29 and immediately in the rear thereof there is a circular rotatable rim 30. Secured to the stationary rim 50 29 is a hollow cylindrical stationary member 31 designed to form a support, about which the rotatable rim may revolve, and the cover 21 is secured at its rear to the rotatable cover support 16 and at its front to the rim 55 30. I preferably extend across the rear of the stationary rim 29 a screen 32 and within the interior of the stationary rim 29 I have detachably fitted a rim 33, the front of which is covered by upholstery 34.

60 Extended horizontally within the phonograph compartment is a partition 35, the under surface of which has secured to it the phonograph operating mechanism indicated by the numeral 36. In the present 65 instance, I have shown electric wires 37 lead-

ing to the phonograph instrument 36 to indicate that it may be operated electrically if desired, and on the top of said partition 35 is a phonograph record support 38 and a reproducing diaphragm and arm 39.

70 Communicating with the arm 39 and arranged below the partition 35 is a phonograph horn 40 which extends upwardly and widens out directly in the rear of the screen 32. I also preferably provide a cloth cover or protector 41 for the under part of the phonograph cabinet which is detachably secured to the lower portion of the stationary member 16 and the sides of the stationary partition 35 to catch the oil or dust and prevent same from getting into the frame of 75 the cabinet of the upholstery.

80 In practical use it is obvious that the general size and shape of the device adapts it very well for a comfortable arm chair and when the two cabinets are closed an observer cannot tell that there is any mechanism contained within the chair. It may be used for all purposes of a chair and may be 85 ornamented and upholstered.

90 When it is desired to use the device as a phonograph the operator simply reaches down at the side of the seat cushion and engages the adjacent edge of the movable cover 21 and pulls it upwardly and outwardly, thus exposing the phonograph compartment and providing ready and easy 95 access to the phonograph. By reaching down at the side of the seat cushion 13 the operator may grasp the movable cover of 100 the record compartment and turn it in the same manner as he previously turned the phonograph compartment and thereby have ready and convenient access to the records, and when the operator is through playing, 105 both of the covers are returned to their normal positions and the phonograph compartment and the record compartment are not only protected from dust but the compartments themselves serve the additional 110 function of being convenient, ornamental and useful parts of the chair proper.

115 I claim as my invention:

120 In a device of the class described, the combination of a chair frame, an arm rest at one side of the seat designed to form a cabinet, said arm rest comprising a stationary rear support, a hub secured to the front thereof, a stationary partition member secured to the front of the hub, a circular rim rotatably mounted upon the hub, a stationary circular rim in the front of the arm member, a cylinder fixed in position in the rear of said stationary rim, a rotatable rim surrounding the stationary cylinder, a horizontal partition fixed between the stationary cylinder and the stationary support in front of the rear hub, a screen at the front of the partition and a detachable upholstered member to close the front of the 125 130

arm rest compartment and a cylindrical cover secured at the front to said rotatable rim and at the rear to said rotatable disk, said cover having an opening therein and so arranged that when rotated to one position it will expose the upper portion and the seat side of the cabinet and when moved to the other position it will cover the cabinet from a point below the top of the seat around the top and outer side of the cabinet, 10 for the purposes stated.

Des Moines, Iowa, January 4, 1922.

LINUS C. HIRT.
